United States Patent Office

Des. 232,276
Patented Aug. 6, 1974

232,276

BIB OR SIMILAR ARTICLE

Lars Marten Andersson, Molnlycke, Inga Gunilla
Margaretha Strandell, Goteborg, and Eric Harry Ove
Svard, Lerum, Sweden, assignors to Molnlycke AB,
Goteborg, Sweden

Filed Apr. 30, 1973, Ser. No. 355,486

Term of patent 14 years

Int. Cl. D2—02

U.S. Cl. D2—226

Fig. 1

Fig. 2

FIG. 3

FIG. 4

FIG. 1 is a front elevational view of a bib or similar article, showing our new design;

FIG. 2 is a like view but with the ties displaced;

FIG. 3 is a front elevational view of a second embodiment of the design of FIG. 1; and

FIG. 4 is a front elevational view of the second embodiment with the ties displaced.

We claim:

The ornamental design for a bib or similar article, as shown and described.
